UNITED STATES PATENT OFFICE.

CLARENCE FREDRICK PEITZMAN, OF GRIMES, IOWA.

AERIAL FOR RADIORECEPTION.

Application filed May 5, 1926. Serial No. 106,897.

This invention relates to radio apparatus, particularly to aerials for the collection of the energy sent out by radio transmitting stations, and has for its object the provision 5 of a novel aerial of peculiar design so constructed and arranged as to be used in conjunction with an already existing aerial but operating to prevent the well known phenomenon commonly known as "fading" in 10 addition to possessing the great advantage of making tuning more selective in enabling the operator of a receiving set to select a desired station even though there is another one of substantially the same wave length 15 operating at the same time.

Another object of the invention is to provide an aerial which will bring in the desired signals with much greater plainness and distinctness than is possible under ordinary circumstances.

A further object is to provide a device of this character which, while possessing the advantages above mentioned, is not likely to bring in any more static or interference 25 than is the case with the employment of the usual type of aerial.

An additional object is the provision of a device of this character which will be simple and inexpensive in manufacture, easy to install or interpose in conjunction with an ordinary aerial, and which will moreover be highly efficient in use, durable in service, and a general improvement in the art.

With the above and other objects and advantages in view, the invention consists in the details of construction and arrangement of parts to be hereinafter more fully described and claimed, and illustrated in the accompanying drawings, in which:—

40 Figure 1 is a side elevation of the device showing it associated with an ordinary aerial.

Figure 2 is a side elevation of the device alone taken on a somewhat larger scale.

45 Figure 3 is a cross section taken on the line 3—3 of Figure 2.

Figure 4 is a detail view showing the wiring connections, and

50 Figure 5 is an elevation of one of the elements alone.

Referring more particularly to the drawings, the letter A designates a support which might be a mast or pole ordinarily used for suspending a radio aerial wire B. The letter C designates an insulator connected

with another support D, in the usual manner, and which might rise from the roof of a house E or other building or support, a lead-in wire F being connected with the wire B at the insulator C and extending down to 60 a switch G having a contact H with which connects a wire I leading into the house for connection with a radio set J. The switch is also shown as having a contact K with which connects a ground wire L for lightning protection when the switch is properly thrown. These details are immaterial but are shown to explain the invention. Connected with the support or mast A by a suitable flexible member M is an insulator N 70 with which, under ordinary circumstances, the aerial wire B would be connected. However, in the present invention, the aerial wire B is not connected directly with the insulator N inasmuch as the device, designated generally by the numeral 10 and constituting the subject matter of this invention is interposed between the insulator N and the aerial wire.

In carrying out the present invention, I 80 have shown the special aerial device designated by the numeral 10, as above mentioned, as comprising a pair of metal disks 11 which may, in actual practice, be conveniently formed of copper coated with tin in order to 85 reduce the likelihood of corrosion under weather influences. Each of these disks 11 is formed with the radial slot 12, the slots in the two disks being reversed so that when the two disks are engaged at the slot they 90 will be in substantially the same relation though arranged at right angles to each other. These disks have their peripheries notched at regularly spaced intervals as indicated at 13, for a purpose to be described. 95

For maintaining the disks in their right angularly arranged relation, use is made of a plurality of brace members 13 which are preferably angular in cross section and welded, soldered, brazed, riveted or otherwise 100 secured to the disks. It is of course apparent that the ends of these brace members are beveled where they engage the disk members 11 so as to provide a proper joint at each place. Obviously, certain of the brace members will be longer than others owing to the fact that the members 11 are of circular shape but this is an immaterial detail and need not be elaborated upon.

Secured to one disk is an arm member 14 110

which is preferably provided with an eye 15 so that the aerial wire B may be connected therewith.

It is intended that the structure defined by the disks 11 be wound with wire indicated at 16 which will therefore define a substantially rectangular structure as shown in Figure 3. One end of this wire is connected with a suspension wire 17 connected with the insulator N, while the other end 18 is brought through an eye 19 on an arm 20 carried by one of the intersecting disk members 11 for connection with a conductor 21 which connects with the aerial wire B as clearly indicated in Figure 1.

In the operation of the device, it has been found that the capacitance of the auxiliary aerial interposed in series with the usual aerial B acts to cut out interference and greatly increase the selectivity of the radio receiving set so that stations from much longer distances, than is ordinarily the case, may be received clearly and distinctly. The exact theory is believed to be immaterial inasmuch as the results are as above mentioned. It is thought that the advantages as well as the construction and operation will be readily apparent to one skilled in the art without further explanation.

30 While I have shown and described the preferred embodiment of the invention, it

should be understood that I reserve the right to make such changes in the form, construction and arrangement of parts as will not depart from the spirit of the invention or the scope of the subjoined claims.

Having thus described the invention, I claim:—

1. A radio receiving aerial comprising a pair of disks secured together in intersecting relation and having their peripheries formed with notches, and a winding of wire engaged within said notches and trained about the assembled disks.

2. A radio receiving aerial comprising a pair of circular plate members mortised together in intersecting relation, and a winding of wire engaged about the plate members at the edges thereof.

3. An auxiliary radio aerial comprising a pair of circular metal plate members slotted radially and interengaged to extend from each other at right angles, supporting means for the plate members, the edges of the plate members being provided with notches, and a wire winding about the plate members engaged within the notches, both ends of the wire winding being connected with the usual radio receiving aerial.

In testimony whereof I affix my signature.

CLARENCE F. PEITZMAN.
